UNITED STATES PATENT OFFICE

LOUIS DUVAL, OF NEWTON, MASSACHUSETTS.

WHEEL-TIRE.

1,109,973.

Specification of Letters Patent.

Patented Sept. 8, 1914.

Application filed August 27, 1913. Serial No. 786,842.

To all whom it may concern:

Be it known that I, LOUIS DUVAL, a citizen of the United States, residing at Newton, in the county of Middlesex, State of Massachusetts, have invented an Improvement in 5 Wheel-Tires, of which the following is a specification.

This invention relates to wheel-tires, and has for its object the construction of a tire 10 comprehending springs attached to the rim and inclosed by a casing, which springs admit of a yielding motion in a vertical direction upon compression and also of a yielding motion in a lateral direction whenever 15 occasion may require, as for instance, when turning sharp corners at a high speed.

Figure 1 is a side elevation of a portion of a wheel-tire embodying this invention, a portion of the casing being cut away. Fig. 2 20 is a longitudinal vertical section of a portion of the tire. Fig. 3 is an enlarged transverse vertical section taken on lines 3—3, Fig. 1.

The body portion of the wheel may be of any well-known or suitable construction, 25 and has a rim 10, which is here shown as having its opposite sides arranged convergently from its outer to its inner face.

A plurality of loop-springs 12 reinforced by spring leaves 12' are arranged about the 30 rim, the ends of which are attached to the opposite sides of the rim, and said springs are disposed radially with respect to the wheel or approximately so. A metallic section 14' is passed around the wheel felly 35 and secured thereto by bolts. This section secures all coöperating parts in relatively fixed relation to the felly, as it overlies and bears upon a portion of the shoe 30, to be later described. Plates 12'' are arranged be- 40 tween the shoe 30 and the block 10, said plates overlying the springs 12. The outer end-portions of said loop-springs are connected together by a circular resilient band 15, to which they are attached by rivets or 45 other means so that they are held in fixed relative positions. Said band is here shown as arranged on the outside of said springs. Said loop-springs admit of a yielding move- 50 ment in a vertical direction and also in a lateral direction, but by themselves are not sufficiently strong and stable to support the weight, and hence they are re-inforced by a plurality of leaf-springs 20, which are ar- 55 ranged within them and which are attached at their outer ends to the outer ends of the

loop-springs and to the resilient band, preferably by the same rivets which are employed to attach the loop-springs to said band, and which are pivotally connected at their inner ends to supports arranged on the 60 rim. The leaf-springs may be composed each of a plurality of leaves of different lengths. The pivotal supports for the leaf-springs may consist of bolts or short bars 25, supported by brackets 26, rigidly secured to 65 the rim, and said bolts or bars are disposed in alignment with the rim and the inner ends of the leaf-springs are loosely arranged on said bolts or bars, and are adapted to swing thereon from side to side, thus admitting 70 of a lateral movement of the leaf-springs in both directions, yet permitting a yielding movement in a vertical direction. The rim and springs supported thereon, or at least the springs, are inclosed by a tire-casing 30, 75 composed of an inner-portion of felt or other material and an outer-portion of raw-hide, leather or other material, which casing itself may be of any well-known or suitable construction, the inner-portion being made 80 thick enough to prevent the edges of the springs from cutting through it.

I claim:

The wheel-tire herein described consisting of a plurality of loop-springs attached at 85 their inner ends to the rim and disposed substantially radially with respect to the wheel, a circular band to which the outer ends of said springs are attached and by which they are held in fixed relative positions with re- 90 spect to each other, a plurality of leaf-springs arranged within and secured to the loop-springs, and means for movably supporting the inner ends of said leaf springs, said means including brackets secured to the 95 wheel rim, pins supported in said brackets and projected at right angles to the axis of the wheel, the leaf springs having openings of greater length than the diameter of the pins, the thickness of the springs at their 100 point of connection to the pins being less than the free length of said pins.

In testimony whereof, I have signed my name to this specification, in the presence of two subscribing witnesses.

LOUIS DUVAL.
